Primary Examiner — Clare E Heflin(74) *Attorney, Agent, or Firm* — McDonnell Boehnen Hulbert & Berghoff LLP.(57) **CLAIM**

The ornamental design for a candle array, as shown and described.

DESCRIPTION

FIG. 1 is a perspective top view of a candle array having the inventive design;

FIG. 2 is a front side view of the candle array shown in FIG. 1;

FIG. 3 is a back side view of the candle array shown in FIG. 1;

FIG. 4 is a left side view of the candle array shown in FIG. 1; FIG. 5 is a right side view of the candle array shown in FIG. 1;

FIG. 6 is a top view of the candle array shown in FIG. 1; and, FIG. 7 is a bottom view of the candle array shown in FIG. 1. The broken lines shown on the drawings depict portions of the candle array that form no part of the claimed design.
